UNITED STATES PATENT OFFICE.

HENRY C. HINCHCLIFF, OF BROOKLYN, NEW YORK.

EYELETING AND SETTING OR LIKE MACHINE.

1,238,519.

Specification of Letters Patent. Patented Aug. 28, 1917.

Application filed September 18, 1916. Serial No. 120,668.

To all whom it may concern:

Be it known that I, HENRY C. HINCHCLIFF, a citizen of the United States, residing at Brooklyn, in the county of Kings and State 5 of New York, have invented new and useful Improvements in Eyeleting and Setting or like Machines, of which the following is a specification.

My invention relates to improvements in 10 eyeleting and setting or like machines and consists in an improved construction and arrangement adapted particularly for securing washers, buttons, snap fasteners or any adaptable article to material by means of 15 eyelets or other suitable fasteners.

My improvements may desirably be embodied in the class of punching and eyeleting machines described in prior Patent No. 1,120,939, dated December 15, 1914, wherein 20 the punch, set and die are arranged permanently to be in axial alinement and in which an anvil is moved between the punch and set and the die.

Valuable features of my invention comprise an improved arrangement of anvil 25 adapted to receive and clamp the pieces to be attached until fastened to the material and thereafter operative to release them to permit their removal and an improved 30 holder for the die which is adapted to be shifted longitudinally or transversely into alinement with the punch and there fastened permanently.

The described and other features of my 35 invention are illustrated in the accompanying drawing wherein like reference characters are applied to the corresponding parts in the several views.

Referring to the drawings, wherein a desirable embodiment of my invention is 40 shown, Figure 1 is a plan view of the parts of my invention. Fig. 2 is a side elevation of the same and also of the punch and set showing an eyelet impaled on the punch and 45 the material punched and elevated for the anvil to pass thereunder.

Fig. 3 is a sectional view on the line A—B showing the piece to be attached brought into alinement with the punch and set; the eyelet pushed through the material 50 and clenched into the button.

Fig. 4 is a sectional view on the line A—B showing the anvil elevated and the piece removed.

Fig. 5— is a cross sectional view at C—D 55 showing the anvils down and a snap fastener attached to the material.

Fig. 6— is a cross section at C—D of the anvil and carrier plate with the anvils elevated. 60

Fig. 7— is a similar cross section showing a modified form of anvil members used when a washer or similar piece is to be attached.

Figs. 8 to 11— illustrate forms of perforated washers and buttons which are attached by the use of the form of anvil shown in Fig. 7. Thereof Figs. 8 and 9 are respectively a sectional view and a plan of the flat type of washer and Figs. 10 and 11 are corresponding views of an approved form of 70 button.

Figs. 12 and 13— illustrate in cross-section commercial types of fasteners adapted to coöperate in the securing or setting operation. 75

The operating parts of these improvements are mounted upon a supporting frame (1) upon which rests holder plate (2), which is provided with a hole having an inclined seat (3^a) in which rests the die holder (4). 80 The holder (4) is recessed to receive the die (5), which is provided with a punch receiving opening (6). The die holder is provided with a passage (7) with which the punch receiving opening (6) registers and through which the pieces of material punched out pass from the die. The frame (1) has an opening (8) larger than the die holder (4) so as to permit of its being moved with the die (5) and the plate (2) horizontally or transversely for properly locating the die centrally with the punch. 85

The upper end of the die holder is provided with an inclined flange (3) which rests upon the inclined seat (3^a) in the plate (2). The lower end of the die holder is threaded to receive a clamping nut (9) which engages the under side of the frame (1). The die holder (4) is slotted at its upper end (10—10) so that said end of the 90 die holder may be compressed to grip the die (5) and bind it and the plate (2) in a desired position upon the frame (1) upon turning the clamping nut (9) and thereby drawing down the inclined flange (3) and the plate (2) upon the frame (1). 100

Thus the die and the die holder are simultaneously secured by tightening of the nut (9). 105

A punch (11) is adapted to co-act with the die (5) to punch a hole in the material in which the eyelet is to set.

5 A set (12) is arranged to engage the eyelet and push it into the hole punched in the material and to set it in the material in co-action with a suitable anvil to be described; this set, as shown, being arranged concentric with the punch.

10 An important feature resides in the means provided for receiving and positioning the pieces to be attached to the material by the eyelet. The means which I have devised for the purpose consists of slidable anvil members (13-13) pivotally attached by the screw (14) to the base (15) which is pivotally attached to the slide plate (16) by the pin (17).

15 The slide plate (16) is provided at (18-18) with inclined sides and at (19) with a hole adapted to freely receive the eyelet.

20 The anvil (13-13) is provided at (20-20) with an inclined seat adapted to co-act with the inclined sides at (18-18) to close the anvil (13) together in a manner hereinafter described. The anvil (13) is provided at (21) with projecting lugs adapted to overlie the articles upon closing of the said anvil 25 thereby clamping the articles in position.

25 An extension spring (22) is retained in place between the anvil members by the stud (23) on the base (15) and its function is to expand the anvil (13) upon its being 30 elevated above the slide plate (16) in a manner hereinafter described.

35 An elevating bar (24) having a projecting stud (25) is slidably mounted in the frame (1) and is adapted to be elevated 40 by the actuating lever (26) fitted to the stud (25) on the bar (24).

45 A lifting finger (27) is mounted upon a vertically operating slide member (28) fitted to a suitable slide-way in the frame (1) and is arranged to be actuated by a lever (30) for elevating the material to permit of the passage of the anvil thereunder. This being performed at a stud 29 on the slide member 28.

50 The operation of the described mechanism in attaching the articles is as follows: The article to be attached by the setting of the eyelet is placed within the lugs (21) and pressed down whereon the seats (20) by engaging the inclined sides (18) force the anvil members inwardly to clamp the article. As will be readily understood, the articles may be so placed by hand or this may be effected automatically if desired. An 55 eyelet is impaled in the punch (11) and the punch then operates to perforate the material and then withdraws and the lifting finger (27) operates to elevate the material. The slide plate (16) then advances until the 60 hole (19) registers with the punch (11) and 65

the latter then moves down with the set to push the eyelet through the material. Thereafter the punch and set and the lifting finger (27) are elevated. The finger lifting the material with the eyelet therein and while so held the anvil (13) with the article therein is advanced into position to co-operate with the set and the punch and set are brought down respectively to guide and set the eyelet into the article within the anvil. 70 75

The operation of the anvil (13) in conjunction with punching and setting is as follows: An article to be attached is placed upon the anvil, while in position shown in Fig. 6 within the lugs (21) and pressed 80 down whereon the seats (20) engage the sides (18) of the slide plate (16) close and clamp the said article therein.

85 The punch (11) and set (12) are now elevated and the anvil (13) with the button attached to the material is elevated above the slide plate (16) when the extension spring (22) opens the anvil and releases the article now attached to the material, the base 90 (15) being raised by the bar (24) at the stud (25) by the lever (26).

95 The slide plate (16) with anvil (13) and base (15) is now returned to its extreme rear position for receiving the next article. The lifting finger (27) is now depressed by the lever (30) to its lower position allowing the die (5) to receive material for another similar cycle of operations.

100 As will be noted, the form of the article to be attached, as illustrated in Figs. 3, 5, 100 12 and 13, is such as to co-operate in effecting the turning out or setting of the end of the eyelet to secure the articles.

105 In Fig. 7 a modified form of the anvil members is shown which are designed to effect the turning over or setting of the eyelet by providing an anvil with a setting surface (31) to be engaged by the lower end of the eyelet to turn over the end to clamp the piece (32) to be attached on end. 110 115

While I have described a desirable and approved embodiment of my invention, it will be readily understood that it is subject to many modifications and variations without departing from the scope of the invention.

120 It is therefore intended that all matters contained herein shall be interpreted as illustrative and not in a limiting sense.

125 In regard to the arrangement of the die holder (4), I am aware that compressible holders have been used for retaining similar tools, but they and their objects have been to self center the parts held, whereas the object here sought is the reverse being to allow of the die being shifted into a proper alignment with its co-acting punch and in practice is desirable, it being commercially impracticable to make parts perfect enough for central alignment otherwise. 130

I claim:

1. In a machine of the character described, the combination of setting means and a movable anvil operative to be advanced beneath the material and to co-act with the setting means to set the eyelet, said anvil being constructed and arranged to receive and clamp an article in position to be attached upon the setting of the eyelet.
- 10 2. In a machine of the character described, the combination of setting means, a movable anvil operative to be advanced beneath the material and to co-act with the setting means to set the eyelet, said anvil being constructed and arranged to receive and clamp an article in position to be attached upon setting of the eyelet and means for releasing the article to permit withdrawal of the material substantially as described.
- 20 3. A machine of the character described comprising means for placing an eyelet in the material, movable anvil members operative to be advanced beneath the material and to co-act with said first means to set the eyelet, said anvil members being constructed and arranged to receive and clamp an article in position to be attached upon the setting of the eyelet, means for locking the anvil members in clamping position and means operative to release the anvil members, after the article has been attached substantially as described.
- 25 4. In a setting machine the combination of a setting tool and an anvil constructed and arranged to receive and clamp articles 35 to be attached to the material operated upon.
5. In a setting machine, the combination with a setting tool of an anvil constructed and arranged to receive and clamp an article and to co-act with the setting tool to 40 set an eyelet through the material and into the article aforesaid, and means for releasing said article after it is fastened to the material.
6. In a machine of the character described, 45 a die supporting member, a die-plate shiftably supported thereon, a die-holder fitted to the plate and clamping means adapted to secure said holder in the machine, said holder having a compressible upper portion having an inclined marginal surface and said plate having a similarly inclined seat to receive said marginal portion and to co-act therewith to clamp the die upon securing the holder to the machine by the 50 clamping means substantially as described.
7. In a setting machine, the combination of a setting tool and an anvil constructed and arranged to receive and clamp an article to be attached upon the setting of an 60 eyelet thereinto, said anvil having setting surfaces to effect the setting of one end of the eyelet substantially as described.

Signed at Brooklyn, in the county of Kings and State of New York, this 16th 65 day of September, 1916.

HENRY C. HINCHCLIFF.
